[57] CLAIM

The ornamental design for a combined handle and escutcheon, as shown and described.

DESCRIPTION

FIG. 1 is a perspective view taken from the top, front and left side of a combined handle and escutcheon showing our new design;

FIG. 2 is a front elevational view thereof;

FIG. 3 is a left side elevational view thereof, the right side being a mirror image of the left side shown;

FIG. 4 is a top plan view thereof, the bottom being a mirror image of the top shown;

FIG. 5 is a rear elevational view thereof.

The fragmentary broken line representations of mounting holes in FIGS. 1, 2, and 5 are for the purpose of illustration only and forms no part of the claimed design.
